UNITED STATES PATENT OFFICE.

JOHN MAXWELL, OF ONEIDA, NEW YORK.

DESIGN FOR A BURIAL-CASKET.

SPECIFICATION forming part of Design No. 18,193, dated March 20, 1888.

Application filed January 19, 1888. Serial No. 261,334. Term of patent 7 years.

To all whom it may concern:

Be it known that I, JOHN MAXWELL, of Oneida, in the county of Madison, in the State of New York, have invented a new and original Design for Burial-Caskets, of which the following, taking in connection with the accompanying drawings, is a full, clear, and exact description.

This design relates to the ornamentation of the corners of burial-caskets; and it consists of the peculiar shape and flutings on said corners, as hereinafter fully described, and specifically set forth in the claim.

In the annexed drawings, Figure 1 is a side view of a burial-casket embodying my design, and Fig. 2 is a horizontal transverse section on line x x , Fig. 1.

Similar letters of reference indicate corresponding parts.

A denotes the body of the casket, and D the lid thereof. The corners C C of the afore-

said body I embellish by rounding the same and providing them with vertical flutings a a .

To better harmonize the base b of the casket with the aforesaid ornamental corners, I form ²⁵ the base with rounded enlargements b' b' , the outlines of which are preferably concentric with those of the corners.

What I claim is—

The design for burial-caskets, consisting of ³⁰ the vertical flutings a a , extending from the base to the top of the corner portions of the casket-body, substantially as described and shown.

In testimony whereof I have hereunto signed ³⁵ my name, in the presence of two witnesses, at Oneida, in the county of Madison, in the State of New York, this 12th day of January, 1888.

JOHN MAXWELL. [L. S.]
